UNITED STATES PATENT OFFICE.

WILLIAM BARTHOLOMEW, OF CHICAGO, ILLINOIS, ASSIGNOR TO TROY LAUNDRY MACHINERY COMPANY, LIMITED, OF CHICAGO, ILLINOIS, A CORPORATION OF NEW YORK.

DRY-ROOM HANGER.

1,025,853.

Specification of Letters Patent.

Patented May 7, 1912.

Application filed February 14, 1910. Serial No. 543,687.

To all whom it may concern:

Be it known that I, WILLIAM BARTHOLOMEW, a citizen of the United States, residing at Chicago, county of Cook, State of Illinois, have invented certain new and useful Improvements in Dry-Room Hangers, of which the following is a specification, reference being had therein to the accompanying drawing.

10 This invention relates to a dry-room hanger and particularly to a construction embodying opposite jaws by which the articles to be dried are suspended therefrom.

The invention has for an object to provide 15 a novel and improved construction of hanger having opposite jaws, one of which is movable relative to the other, with latching means mounted to automatically retain the jaws in open position until they are released therefrom by the operator when inserting goods to be dried within the jaws.

A further object of the invention is to provide a support upon the hanger having a coöperating stripper connected to a movable jaw for automatic operation to discharge goods from the support in the opening movement of the jaws.

Other and further objects and advantages of the invention will be hereinafter set forth 30 and the novel features thereof defined by the appended claims.

In the drawings—Figure 1 is a front elevation of the hanger and its support; Fig. 2 is an enlarged end view of the hanger; Fig. 3 is a detail perspective of the movable jaw; Fig. 4 is a similar view of the fixed jaw; Fig. 5 is a vertical section of the jaws in closed position; Fig. 6 is a similar view of the jaws in open position; Fig. 7 is a detail elevation of the jaws and stripper; Fig. 8 is a detail perspective of the stripper; Fig. 9 is a vertical section showing a modified form of stripper; Fig. 10 is a similar view of this modification in discharging position; and Fig. 11 is a detail perspective of the modified form of stripper.

Like numerals of reference refer to like parts in the several figures of the drawings.

The numeral 10 designates the hanger bar 50 which may be of any desired construction, for instance provided with the cross bar 11 at its bottom and the usual chain link connection 12. This hanger may be supported in any ordinary manner, for instance by the 55 carrier wheels 13 traversing the track 14

from which depending arms 15 extend at each side of the hanger and are provided with inclined faces 16 adapted to operate the movable supporting jaw as will be hereinafter described.

The fixed jaw 17 may be of any preferred construction, for instance bent from sheet material as shown in Fig. 4, to form a U-shaped jaw having side flanges 18 between which a gripping block 19 is secured, for 65 instance by means of a rivet 20. This block is preferably formed of wood or other material which would prevent injury or discoloration by rust of the goods held thereby. The fixed jaw is secured in position upon 70 the cross bar 11 by means of the arm 21 extended from one of the side walls 18 and properly secured to the bar. Within these side walls, the movable jaw 22 is disposed and the side walls 23 thereof are pivoted to 75 the walls 18 of the fixed jaw by means of a cotter pin or other suitable pivot 24 extending through the aperture 25 of the fixed jaw and the aperture 26 of the movable jaw. Intermediate the walls 23 of the movable 80 jaw, a gripping block 27 is secured and is similar to the block 19 before described so as to engage and coöperate therewith as shown in Fig. 5. These jaws are normally held in engagement or pressed toward each 85 other by means of the tension spring 28 which surrounds the pivot 24 and bears at its free ends against the upper portion of each jaw.

For the purpose of automatically retaining the jaws in open position, after they are opened to discharge goods therefrom, a latch lever 30 is pivotally mounted at 31 upon the fixed jaw either by means of a cotter pin 32 or other form of pivot. This lever extends 90 through an aperture 33 in the end wall of the movable jaw 22 and the lever is formed with a holding face or shoulder 34 to engage the wall of the movable jaw as shown in Fig. 6 and also with an operating handle 35 95 by which the lever may be raised to release the jaws as goods are inserted between them. Under some conditions of use, it is desirable to provide upon the hanger a support upon which collars, cuffs or other articles can be 100 suspended during the drying action and to automatically strip or discharge such articles from the support when the jaws are opened. One form of such support is herein shown and comprises a hook or pin 36 se- 110

cured to the outer face of the fixed jaw 17. Coöoperating with this pin is a stripper plate 37 having a bifurcated upper end 38 extended laterally therefrom and pivotally mounted at 39 upon the fixed jaw by means of a cotter pin 40 or other pivoting means. The lower end of the stripper plate is provided with a longitudinal slot 41 through which the supporting hook 36 extends. Ex-
10 tending upward from the inner end of the portion 38 is a lever arm 42 having a longitudinal slot 43 therein through which a pin 44 carried by the movable jaw 22 extends and travels in the movement of said jaw so
15 as to shift the stripper plate from the full line position shown in Fig. 1 to that shown by dotted lines therein and thus remove goods from the support. The movable jaw in its return movement engages the latch lever and is
20 held in open position while the stripper blade returns sufficiently to leave the free end of the support exposed so that articles may be hung therein before the jaws are again closed, as shown in Fig. 7.
25 In Figs. 9, 10 and 11, a modified form of the stripper device is shown and coöperates with the pin or hook 45 carried by the fixed jaw 17. This stripper comprises a lever 46 having an angular portion 47 at its upper
30 end provided with a longitudinal slot 48 and pivoted at 49 upon the movable jaw 22. The lower end of the lever 46 is provided with a looped portion 50 which embraces the support 45. Extending through the slot 48
35 is a pin 51 carried by the fixed jaw while the upper end of this jaw is slotted at 52 and the angular portion 48 of the lever extends therethrough. By reference to Figs. 9 and 10, it will be seen that a movement of
40 the upper end of the movable jaw toward the end of the fixed jaw produces an upward swinging movement of the lever 46 and thus strips articles from the support 45 when the jaws are fully opened, as shown by dotted
45 lines in Fig. 10, while when the jaws are latched in open position, the stripper returns to the full line position shown in that figure. The operation of this form of stripper is substantially the same as that first de-
50 scribed.

In the application of the invention, one set of jaws may be used, but for the purpose of supporting articles at two points, the hanger is shown with two sets of jaws which
55 also greatly increase the capacity thereof for both shirts, rough dry work and other articles. The application of the support to the hanger in connection with the stripper, automatically operated by the jaws, further
60 increases the capacity of the conveyer and dry-room, permitting the support of collars, cuffs and other similar articles at one side or end of the hanger.

In the operation of the invention, the jaws
65 may be manually actuated to release articles

therefrom or automatically operated by the inclines shown in Fig. 1, and in either event, are automatically latched in open position as the lever, riding upon the edge of the slot in the movable jaw, drops by gravity into contact with this edge as the jaws start to close under tension of their spring. This prevents the necessity of the operator using his hand to open the jaws for the insertion of the goods and greatly reduces the time required to refill the conveyer after one lot of goods has been discharged therefrom. When the operator inserts the goods between the jaws, it is only necessary to slightly raise the lever by the upward movement of his hand incident to inserting the goods and the jaws are thus automatically closed to grip the goods. The construction of the jaws secures the utmost rigidity with an economy of construction and presents gripping faces which prevent injury to the goods and can be replaced whenever desired. The action of the stripper is entirely automatic in the movement of the jaws and after removing goods from the support, leaves an exposed end thereof upon which fresh goods can be suspended before and after closing the jaws.

It will thus be seen that the invention presents a simple, efficient and economically constructed form of combination hanger adapted to support all classes of goods while traversing a drying room and one in which the discharging action for both the jaws and stripper may be automatically effected and the jaws also automatically held in open position for the introduction of other goods.

Having described my invention and set forth its merits what I claim and desire to secure by Letters Patent is—

1. In a dry-room hanger, the combination with a support, of a fixed jaw having parallel side flanges and a supporting arm extending from one of said flanges for supporting said jaw in vertical position, a movable vertical jaw provided with parallel side flanges pivotally mounted between the flanges of the fixed jaw, gripping blocks disposed between the flanges of said jaws at their lower ends, means for holding said blocks in contact, an independently movable latch lever pivoted horizontally between the side flanges of the fixed jaw and having its free end extending through an aperture in the movable jaw, and means carried by said lever to engage a wall of said aperture when said movable jaw is moved into open position.

2. In a dry-room hanger, the combination with a carrier, of a hanger provided with a fixed and a movable retaining jaw, a releasing device adapted to be interposed between the hanger and the movable jaw, and an independently movable latch lever pivoted horizontally on the fixed jaw and having its

- free end extending through an aperture in the movable jaw, and means carried by said lever to engage a wall of said aperture when said movable jaw is moved into open position.
5. In a dry-room hanger, opposite jaws one of which is movable relatively to the other, a goods support carried by one of the jaws, and a coöperating stripping device connected to the movable jaw to discharge goods from said support by the opening movement of said jaws.
10. In a dry-room hanger, opposite jaws one of which is movable relatively to the other, a goods support carried by one of the jaws, and a coöperating stripping device connected to the movable jaw for automatic operation to discharge goods from said support in the opening movement of said jaws.
15. In a dry-room hanger, opposite jaws one of which is movable relatively to the other, a goods support, and a stripping lever embracing said support and connected to a movable jaw for movement thereby.
20. In a dry-room hanger, opposite jaws one of which is movable relatively to the other, a goods support, and a stripping lever having an open portion to embrace said support and an angular portion provided with a slot connected with a movable jaw.
25. In a dry-room hanger, opposite jaws one of which is movable relatively to the other, a goods support, and a stripping lever pro-
- vided with a slot to embrace said support and pivotally mounted upon one jaw, and an arm carried by said lever and provided with an elongated slot to engage a projection from the opposite jaw.
30. In a dry-room hanger, a fixed jaw, a coöperating movable jaw, a support carried by a wall of the fixed jaw, and a stripping device mounted upon the fixed jaw and connected to the movable jaw for operation thereby.
35. In a dry-room hanger, a fixed jaw, a coöperating movable jaw, a support carried by a wall of the fixed jaw, and a stripping lever pivoted upon the fixed jaw and embracing said support and connected to the movable jaw for operation thereby.
40. In a dry-room hanger, a fixed jaw, a coöperating movable jaw, a support carried by a wall of the fixed jaw, and a stripping lever pivoted upon the fixed jaw and embracing said support and connected to the movable jaw for operation thereby.
45. In a dry-room hanger, a fixed jaw, a coöperating movable jaw, a support carried by a wall of the fixed jaw, a stripping lever pivoted upon said fixed jaw and provided with an apertured depending portion embracing said support, and an arm from said lever provided with an elongated slot adapted to engage a projection from the movable jaw.
50. In testimony whereof I affix my signature in presence of two witnesses.
